United States Patent Office

Des. 192,997
Patented June 12, 1962

192,997

GOLF CAR OR THE LIKE

Harry E. McCrady, Wallingford, and Arthur I. Countryman, Hamden, Conn., assignors to The Snow-Nabstedt Gear Corporation, Hamden, Conn., a corporation of Connecticut

Filed June 30, 1961, Ser. No. 65,774

Term of patent 14 years

(Cl. D14—3)

Fig.1.

Fig.2.

Fig.3.

FIG. 1 is a front perspective view of a golf car showing our new design;

FIG. 2 is a perspective view taken from the top; and
FIG. 3 is a rear perspective view thereof.

The dominant features of our design reside in the portions shown in full lines. The side not shown is a mirror image of the side shown.

We claim:

The ornamental design for a golf car or the like, substantially as shown and described.
